UNITED STATES PATENT OFFICE.

EMIL GATHMANN, OF BALTIMORE, MARYLAND.

FUSE MECHANISM FOR PROJECTILES.

1,296,070.

Specification of Letters Patent.

Patented Mar. 4, 1919.

Application filed September 7, 1917. Serial No. 190,218.

To all whom it may concern:

Be it known that I, EMIL GATHMANN, a citizen of the United States, residing at Baltimore, in the State of Maryland, have invented certain new and useful Improvements in Fuse Mechanism for Projectiles; and I do hereby declare the following to be a full, clear, and exact description of the same, reference being had to the accompanying drawings, forming part of this specification.

In the fuse mechanism commonly employed in connection with projectiles designed to be fragmented by an internal bursting charge, provision is made whereby a time train or fuse will be lighted during the initial movement of the projectile under the influence of the propelling charge, and the length of the fuse or train determines the period of time intervening between the discharge of the projectile and the time when the bursting charge is ignited. Ordinarily, the time train is ignited while the projectile is well within the bore of the gun, the common arrangement being a percussion primer or detonator which is fired by an inertia member which tends to remain stationary, while the projectile and the body of the fuse move forwardly with relation thereto with the result that the primer or detonator is exploded during the acceleration movement of the projectile. This arrangement has developed irregularities in action and produced conditions which under some circumstances have caused premature explosion. The irregularity in action is thought to be largely due to the fact that the projectile in moving forwardly in the bore of the gun necessarily compresses and expels the volume of air in the gun bore and the longer the gun, the greater the compression and volume of air necessarily expelled. The time or fuse train burns more rapidly under increased air pressure, and inasmuch as the air pressure has direct access to the time train there may be as much as two or three seconds difference in the rate of burning, although the time interval may be as little as $\frac{2}{100}$ of a second. Roughly speaking, each inch of barometer pressure or each half pound pressure of the air increases the rate of burning $\frac{4}{10}$ of a second on a 21-second burning fuse. As it is possible that the air

pressure surrounding the fuse, while in the bore of the gun, may be as high as 100 pounds per square inch, it will be readily appreciated that the error or unequal burning will be a marked factor for which empirical adjustment must be made. Tests indicate that the error found to exist when a projectile is fired from a long gun is as much as ten times that which occurs when the projectile is fired from a short or field gun.

The object of the present invention is to overcome the errors pointed out and to provide a detonator mechanism which will ignite the time train at a time when it is not subjected to the air pressure within the bore of the gun, but, on the contrary, when it has actually begun its flight from the muzzle of the gun. In the preferred arrangement, provision is made whereby the detonator will be exploded immediately after the projectile has received its maximum acceleration or has acquired its greatest velocity, this usually occurring at from 10 to 30 feet from the muzzle of the gun.

Other objects of the present invention are to provide a fuse mechanism embodying an inertia member and a firing member relatively movable in opposite directions for arming the fuse and movable in the same direction for firing, with locking mechanism intermediate the inertia and firing members for retaining them in their relative positions for safety or for firing as the case may be whereby firing may be effected subsequent to the maximum acceleration of the projectile.

In the accompanying drawings

Figure 1 is a section in a plane longitudinally of the axis of a fuse embodying the present invention with the parts in their normal or safety positions.

Fig. 2 is a similar view with the parts in armed position.

Fig. 3 is a similar view with the parts in firing position.

Fig. 4 is a view showing a centrifugally operated safety lock.

Like reference characters throughout the several figures indicate the same parts.

The fuse mechanism adopted for illustrating the invention embodies many features which correspond to what might be termed standard practice, in that such mechanisms are in common use and have been manufactured on a large scale; that is to say, there

is a body portion A which is usually made of brass and is adapted to be secured by a screw-thread connection in the nose portion of the projectile in a housing, which housing is in turn secured in the nose portion of the projectile. A forwardly extending stem-like portion A' of the fuse body A serves as the support for one or more rings or annular bodies B, B', and a cap or nut C which is threaded on the end of the stem and retains the rings in position. The cap C and stem itself are formed with an internal chamber preferably of cylindrical formation, for the reception of the firing mechanism of the detonator to be presently described. The rings B, B' are provided with internal passages in which the time train or fuse composition D, D' is located, and one of the rings is usually made adjustable about the stem for setting the length of the time train, whereby the period during which the train will burn may be set at any point from zero to the full length of the train and time for which it is designed. This construction is well known and is preferably in accord with so-called standard practice. To permit fumes to escape during the combustion of the time train, the fuse mechanism is provided with vent openings E usually located in the cap piece C and having their external ports beneath an overhanging part or flange e forming a part of said cap.

In the simple embodiment of the invention illustrated in the drawings the cap or detonator for igniting the time train or the magazine charge if no time train is employed, is mounted in fixed position and a movable firing pin is adapted to coöperate therewith to effect detonation but in accord with well known and usual practice this arrangement may be reversed, the pin being stationary and the cap or detonator movable. As shown the cap or detonator F is mounted in the bottom of a capsule formed in two parts G and G' for convenience in manufacture and charging and the capsule is held in the forward end of the body A' preferably by a screw thread connection as shown.

In the rear of the capsule G the body of the fuse is formed with an axial chamber for the reception of the movable members of the firing mechanism which members are preferably inserted from the rear end of the chamber and retained by a closure cap or screw plug H.

The movable members referred to comprise an inertia member I and a firing member K. These members preferably have certain characteristics to be presently referred to and a locking device is employed adapted to hold them in relative position when the fuse is unarmed, which locking device is effective save against forces such as are set

up during the discharge of the projectile from the gun but adapted to permit of relative movement when subjected to such forces. When the relative movement takes place then the locking device locks the members together to act as a unit in firing the detonator or cap. 70

The inertia member I is conveniently made in two parts I and I' to form a chamber for the reception of a split ring i of 75 such diameter as to normally project or overhang into the central bore of the member and in position to coöperate with the inclined shoulder k on the firing member K. The body of the firing member is preferably cylindrical and provided with a groove k' for the reception of the split ring when relative movement of the members has taken place to lock them together and with a shoulder K² for arresting the movement of 80 the inertia member. At its rear end the firing member normally seats against the closure H and it may be lightly retained in such position by spring retainers M as shown in Figs. 1, 2 and 3 or by a centrifugally released locking member N as shown in Fig. 4. 90

A coil spring or rebound member O is mounted in the chamber in rear of the inertia member I which spring is normally expanded as shown in Fig. 1 but is adapted to be compressed when the inertia member moves rearwardly as shown in Fig. 2. The inertia member normally rests against the front end of its chamber or the shoulder P at the front end of its chamber and its 100 rearward movement is finally checked by the shoulder k² on the firing member. 95

In operation it may be assumed the parts are normally in the position shown in Fig. 1 and when the projectile is fired from the gun the inertia of the member I will tend to resist its movement with the projectile resulting in a relative backward movement of said member to the position shown in Fig. 2. Before such relative movement can 110 take place the resistance of the split ring must be overcome and when it has taken place the split ring locks the inertia and firing members together. The movement will compress the rebound member and this condition will prevail during the time the projectile is accelerating but after the maximum acceleration and usually a short distance beyond the muzzle of the gun the rebound member asserts itself and drives the 115 inertia member and the firing member locked thereto, forwardly to the position shown in Fig. 3 when the point strikes the cap or detonator and fires the same. Thereafter the action is similar to the action of the ordinary fuse now in use. Under some circumstances and for some uses it is desirable to provide additional safety means such for example, as the centrifugally withdrawn lock N which is thrown back against the

120
125

tension of its spring by the spinning of the projectile due to the rifling of the gun barrel.

To further protect the cap or detonator 5 diaphragms such as at R, R' of thin easily perforated material may be interposed between the firing member and caps.

It will be noted that the fuse is of simple construction, the parts being of such form that they may be manufactured and assembled with the greatest facility. When assembled none of the parts are under tension and consequently deterioration cannot render the device unsafe or cause a movement which will accidentally arm the fuse. The arming movements can only be effected by the discharge of the projectile from the gun and the actual firing of the cap only takes place after the projectile has left the muzzle of the gun.

From the foregoing it will be seen that the inertia member normally stands at the forward extreme of its movement and the firing member is in such position that the cap or detonator is spaced from the firing pin but when the inertia member is moved to the rear and coupled to the firing member the relation of the two members is so changed that when the inertia member moves to the forward extreme of its movement the firing member will advance with it and the cap or detonator will be brought into engagement with the firing pin and fired. The retainers M perform a secondary function in that they exert a tendency to hold the parts in armed position until the other forces tending to hold the parts in this position are overbalanced when they release and the inertia member and firing member will advance with a jump or quick movement. Such devices are not essential but add to the efficiency of the fuse.

What I claim is:

1. A fuse embodying a forwardly movable firing member, a rearwardly movable inertia member, a resilient rebound member for resisting the rearward movement of the inertia member independently of the firing member, means for coupling the firing member and inertia members together for simultaneous forward movement under the influence of the rebound member whereby the fuse will be armed during acceleration of the projectile and fired after maximum acceleration has been attained.

2. A fuse embodying a rearwardly movable inertia member, a resilient rebound member for normally holding the inertia member at the forward extreme of its movement independently of the firing member and returning the same to such position after rear-

ward movement due to its inertia and a firing member normally held in unarmed position and connections whereby the firing member will be advanced by the inertia member during its rebound or forward movement to fire the detonator. 65

3. A fuse embodying a rearwardly movable inertia member, a resilient rebound member for normally holding the inertia member at the forward extreme of its movement independently of the firing member and returning the same to such position after rearward movement due to its inertia and a firing member movable with relation to the 70 inertia member from an unarmed into an armed position and connections whereby the firing member is carried forwardly by the inertia member during the rebound movement of the latter and with the firing member 75 in its armed position with relation to the inertia member to fire the detonator.

4. A fuse of the character specified in claim 3 embodying releasable means for locking the inertia and firing members in unarmed relation, and means for locking said parts in their armed relation. 85

5. A fuse of the character specified in claim 3 embodying a yielding lock for retaining the inertia and firing members in 90 either armed or unarmed relation to each other.

6. A fuse of the character specified in claim 3 embodying an inertia member having an axial opening and a firing member 95 mounted in said opening and means for holding the firing member against a rearward movement with relation to the inertia member and permitting said members to move forwardly in unison. 100

7. A fuse of the character specified in claim 3 embodying means for temporarily restraining the forward movement of the inertia and firing members to cause sudden acceleration of such movement. 105

8. In a fuse the combination with a fuse body having a central bore forming front and rear chambers with a shoulder at the forward end of the rear chamber, of a cap or detonator member fixed in the front chamber and facing rearwardly an inertia member movably mounted in the rear chamber, a resilient rebound member normally holding the inertia member forwardly against the said shoulder, a forwardly movable firing member mounted in the rear chamber and means for coupling the inertia and firing members for simultaneous forward movement during the rebound or forward movement of the inertia member. 110 115
